GAS TURBINE FUEL CONTROL SYSTEM FOR PREVENTING COMPRESSOR STALL

Daniel G. Russ, Hatboro, Pa., and James M. Eastman, South Bend, Ind., assignors to The Bendix Corporation, a corporation of Delaware

Filed Feb. 23, 1956, Ser. No. 567,261

10 Claims. (Cl. 60—39.28)

This invention relates to fuel feeding systems and more particularly to a fuel scheduling system for gas turbine engines.

Fuel systems for gas turbine engines normally must deal with two factors which limit fuel flow during acceleration. These are first, combustion chamber or turbine inlet temperature and second, compressor stall. Because of problems related to distribution errors and the difficulty of obtaining sensitive, but durable, temperature sensing elements, it is considered desirable that these limits be avoided without measurement of either engine or turbine inlet temperature. An expression may be derived for fuel flow scheduled to give a constant maximum turbine inlet temperature. This expression is as follows:

$W_f = \delta N F_t(N, r)$ where

W_f = weight of fuel flow in pounds per hour

δ = compressor inlet total pressure corrected for standard conditions

N = engine r.p.m.

r = compressor pressure ratio.

It has been demonstrated that compressor stall will be avoided if fuel is scheduled to the engine according to the equation $W_f = \delta N F_s(r)$.

Each of the above expressions utilizes the same three engine operating conditions; namely, δ , N , and r , and neither of these equations involves temperature sensing. A control which meters according to these two equations in such manner that the equation permitting the least fuel is always overriding will schedule constant turbine temperature accelerations with overriding stall protection. It is, therefore, an object of the present invention to provide a fuel control system which will utilize the above relations in mutually overriding fashion to schedule fuel.

It is another object to provide a control system which will schedule fuel very close to temperature and stall limits of the engine without the necessity for actually sensing temperature.

It is a further object to provide a fuel feeding system which will accomplish the above objects and which requires that a minimum number of engine operating conditions be sensed.

Other objects and advantages will become apparent from perusal of the following specification taken in connection with the accompanying drawings, in which:

FIGURE 1 shows fuel requirements for a typical turbo-prop engine based on the above equations and with the turbine inlet temperature established at a uniform maximum value; and

FIGURE 2 is a schematic drawing of a control which meters fuel according to the above equations.

With reference to FIGURE 1, it will be seen that this drawing is a graph showing acceleration flow limits for a typical turbo-prop engine in which the vertical axis is plotted in terms of weight or fuel flow corrected for speed and standard temperature conditions and the horizontal axis is plotted in terms of compressor pressure ratio. While the present specification refers to compressor pressure ratio, this term will be considered as including the ratio of any pressures sensed across any part of the compressor which will vary in substantially the same manner as does the ratio across the entire compressor. On this graph curves a , b and c are all maximum

2

temperature lines for different values of compressor inlet temperature. Curve d which intersects both curves a and b defines the boundary of the compressor stall area. For all but very high temperatures at the compressor inlet, the stall area will intersect the maximum temperature limit line. Curves e_1 through e_8 define the relation of the corrected fuel flow

$$\frac{(W_f)}{(\delta N)}$$

to pressure ratio at specific values of N . The family of curves e hence describes the corrected fuel flow as the composite function $f(N, r)$. If the limiting value of $W_f/\delta N$ occurs when the curve e is reached and if curve e is shifted as shown when N is changed, then the values of

$$\frac{W_f}{\delta N}$$

20 will coincide with those for curves a , b and c , and the required limitation of fuel flow to limit turbine inlet temperature will be obtained.

A control which is to provide an optimum acceleration for an engine such as that for which the curves of FIGURE 1 were plotted must schedule at maximum temperature up to the compressor stall area, follow the boundary of the compressor stall area until maximum temperature or requested speed is reached, and then govern back to steady state fuel flow at maximum speed. The present 25 application is concerned entirely with an acceleration control and has not included means for speed governing, which might be accomplished by any of several well-known methods. For the purpose of discussing operation of the present device, it will be assumed that an all-speed governor is arranged to control a valve downstream of valve 18.

From the foregoing it will be apparent that if the area A_m of a valve can be made responsive to N and r such that the area varies as a function of engine speed and 30 compressor pressure ratio during accelerations in the region where fuel flow is limited by temperature and as a function of compressor pressure ratio only during the acceleration range over which stall conditions may be encountered and that the head across the valve varies directly as a function of δ and engine speed, it should be possible to meter fuel to the engine in accordance with the above equations. Such a control system is shown 35 in FIGURE 2. In this control system fuel is supplied from a source, not shown, through a conduit 10 to a fluid pressurizing device shown herein as a variable displacement pump 12. Fuel from this pump is supplied through a conduit 14 to a head regulating system which controls the head across a metering valve 18. The axial position of valve 18 and, hence, its area is controlled by an actuator shown generally at numeral 20. The pump is of a 40 conventional design having a number of pistons 22 arranged to reciprocate in their respective chambers 24. A spring 26 in each one of these chambers urges the piston 22 to its maximum outward position. The pistons 22 have imparted thereto a reciprocating motion through the 45 action of a cam plate 28 which is drivably attached to a shaft 30. This shaft is directly attached to the engine, not shown, and rotates at a speed directly proportional to engine speed. The number of reciprocations which each piston makes in a given period of time, then, will be defined by the speed of rotation of shaft 30. The 50 amount of fuel which is pumped during each cycle of a plunger 22 is dependent upon the angle of the cam plate 28. A shaft 32 drives this cam plate 28 and is positioned 55 through the action of the forces exerted on each side of a piston 34 in a chamber 36. As shown, the pressure on the bottom side of piston 34 is pump delivery pressure,

while working against this pressure on the top side of piston 34 is a servo pressure in chamber 36 and also the force exerted through the action of a spring 38. An evacuated aneroid member 40 exposed to ambient pressures supplies a signal varying with changes in δ to a conventional servo pressure control valve 42 which, in turn, controls servo pressure in the chamber 36 by varying the effective flow area of a vent passage 43 connected between the chamber 36 and a suitable source of drain pressure, not shown. The servo valve 42 by controlling the pressure above piston 34 causes the piston to move in proportion with the pressure δ so as to cause fuel displacement per pump revolution to vary in proportion with δ . It can be seen that the pump output varies in proportion with the product δN .

The output of pump 12 is supplied through conduit 14 to a regulator system 16 and to the main metering valve 18. Regulator system 16 includes a fixed orifice 46 and chambers 48 and 50 communicating with the fuel pressure upstream and downstream respectively of the fixed orifice. These will be referred to as P_1 and P_2 pressures, respectively. Immediately upstream of metering valve 18 is a chamber 52 containing a control pressure which will be referred to as P_3 pressure and downstream of valve 18 a conduit 54 connects a chamber 56 with metered fuel pressure or P_4 pressure. Chambers 48 and 50 and chambers 52 and 56 are separated by means of two equal area diaphragms 58 and 60, which are lightly loaded by two opposing springs 62 and 64. These diaphragms are each connected to a shaft 66 carrying the regulator metering valve elements 68. By means of this arrangement the pressure difference ($P_3 - P_4$) across the control valve 18 is maintained at the value ($P_1 - P_2$) by controlling by-pass fuel which flows through a conduit 70 across valve element 68 and through a conduit 72 to the inlet side of pump 12. Metered fuel crossing valve 18 is supplied to the engine, not shown, through a conduit 74.

The axial position of valve 18 is controlled by means of an actuator 20 which has as a means of providing a speed input an engine driven shaft 75 having mounted thereon a pair of governor weights 76. These weights act to produce a translation of a shaft 78 which, in turn, carries an arm 80 having mounted on its extreme end thereof means for controlling the flow through an orifice 82. Also supplied as an inlet to actuator 20 is a servo pressure of comparatively high value which enters through a conduit 84. It will be observed that it is this high servo pressure as modified by the action of a bleed 86 which is controlled through the movement of lever arm 80. This servo pressure is also supplied to a chamber 88 where it acts to push a piston 90 in a leftward direction against the force of a spring 92 and also against a spring 94. A shaft 96 is carried by piston 90 and seeks an axial position dependent upon the balance of the forces exerted by springs 92 and 94, lever arm 80, and the fluid pressure in chamber 88. A cam 98 is anchored at one end to the housing of actuator 20 and is pinned to shaft 96 in such manner as to rotate around its anchor point. The angular position of cam member 98 is proportional to engine speed and by means of a contour ground on the face 100 of said cam any desired function of engine speed may be imparted.

High servo pressure from conduit 84 is also supplied through a fixed area orifice 102 and a variable area orifice 104 to a central chamber 106 which is in direct communication with the return side of the servo pressure system via conduit 108. An intermediate control pressure downstream of orifice 102 is supplied to a chamber 110 where it exerts a force tending to push a piston 112 to the left against the action of a spring 114. Carried by piston 112 is a shaft 116 having positioned on the left end thereof a roller 118. A shaft 120 is attached to roller 118 and also to a roller 122. Roller 118 moves between a fixed track formed by part of the

housing of actuator 20 and a tiltable bar or rod 124 which is suspended from a bellows 126 responsive to compressor inlet pressure by a link 128 and an additional bellows 130 responsive to compressor discharge pressure by a link 132. It will be observed that link 132 also acts to vary the effective area of orifice 104. This structure acts to position shaft 120 as a function of compressor pressure ratio and operates as follows:

When the engine is at rest, the pressures on the exteriors of bellows 126 and 130 are equal and the pull or upward forces exerted on the opposite ends of the rocking bar 124 are equal. The pressure in chamber 110 being at this time relatively high due to the restriction of orifice 104 by member 132, piston 112 is forced to the left thereby pushing roller 118 to its extreme lefthand position. As soon as the engine starts, there is a build-up of compressor outlet pressure on the outside of bellows 130. This causes the bellows to contract which moves member 132 away from orifice 104, allowing the pressure in chamber 110 to escape into chamber 106. As a result, spring 114 pushes piston 112, and hence, roller 118, to the right until its force is balanced by the pressure remaining in chamber 110. Since the upward forces exerted by bellows 130 and 126 are proportional to compressor inlet and outlet pressures, respectively, the quotient or geometrical ratio of these forces is proportional to compressor ratio. This positions roller 118 and, hence, shaft 120 at a point of equilibrium for the then existing compressor ratio.

Roller 122 rides on a tiltable bar or beam 134 which is attached at its left end to the housing of actuator 20 and supported on its other end by means of a spring 136. Attached to the right end of beam 134 is a link 138 drivably attached to metering valve 18. Also pivoted on housing 20 at the same point as beam 134 is a lever 140 having on one end thereof a roller 142 which rides on face 100 of cam 98 and on the opposite end on a cam face 144 arranged to exert a force against roller 122. Also arranged to effect the position of roller 122 is a stationary cam 146. Cam 146 has ground thereon a contour designed to limit the upward movement of roller 122 and, hence, the upward movement of link 138 over the compressor stall region so as to hold valve 18 to a limited area. Because of the movement of cam 98, lever 140 will tilt in relation to speed and the cooperative movement of cam face 144 and shaft 120 acts to impart to beam 134 and, hence, to link 138 a position varying with speed and compressor pressure ratio.

In considering the operation of the above device, it would be desirable to discuss a typical acceleration with reference to FIGURE 1. Consider first an engine operating at point A on the graph. This may be considered an idle condition, the pressure being at a very low value as is corrected fuel flow. The fuel flow is controlled by the governor and held below the limit shown on FIGURE 1. Assume the pilot requests the governor to give maximum r.p.m. The entire flow output of valve 18 will then enter the engine. This will cause temperature and pressure ratio to rise until point B on FIGURE 1 is reached. Note this is the flow which gives the maximum permissible turbine inlet temperature. The engine now accelerates and r.p.m. and pressure ratio increase simultaneously to describe an operating path along curve b until point C is reached. It will be remembered that curves a, b and c all represent corrected fuel flow for the same maximum temperature at different ambient temperature conditions. For a hotter or colder day, then, point B might lie on a curve roughly parallel to any of a, b or c. As fuel flow increases from point A to point B, there would be some increase in the amount of fuel delivered by pump 12, and an increase in the speed of governor weight 76 and, hence, a change in the angular position of cam 98. Between point A and point B the roller 122 and actuator 20 is

substantially at its extreme lefthand position of travel. This position is effected only slightly through the change in compressor pressure ratio and there is negligible change in engine r.p.m. during this time. At point B the speed factor which is introduced on cam 98 and the compressor ratio factor on piston 112 become significant and roller 118 begins to operate to move roller 122 to the right. As roller 122 moves to the right, and cam 144 simultaneously moves clockwise, a gradually increasing rate of fuel flow is permitted until roller 122 meets cam 146 which is the compressor stall cam. Further movement to the right of roller 122 causes the roller to be forced in a downward direction thus forcing beam 134 and shaft 138 downwardly and reducing the effective area of valve 18. The range of increase in fuel flow just described occurs from point B to point C on FIGURE 1 and the intersection of the temperature line with the stall line occurs at point C. At point C roller 122 begins to follow cam 146 and the fuel flow is reduced as will be seen by examination of curve d. As the danger of entering compressor stall decreases, the stall cam will allow an increased rate of fuel flow until flow is again equivalent to that permitted by the maximum temperature line b. This occurs at point D on the graph. Fuel flow then continues at maximum temperature until the speed governor brings the fuel flow to the value necessary to support steady state operation at the desired increased speed. It will be observed that on curve b the compressor stall area did not interpose a serious interruption in the fuel flow schedule. It was, however, necessary to interrupt curve b as shown from C to D in order to avoid running the engine into compressor stall. For colder days this interruption would be more severe as will be appreciated from examination of curve a.

Although only one embodiment is shown herein, it is recognized that the teachings of this invention may take a number of forms and modifications may be made to suit individual requirements.

We claim:

1. An acceleration limiting system for an engine having a compressor, a combustion chamber, and a fuel conduit for conducting fuel to the combustion chamber comprising a metering valve operative to control the fuel flow through said conduit; a head regulator for controlling the pressure drop across said valve; a fluid pressure source for supplying fuel to said conduit having means for varying its output with changes in compressor inlet pressure and engine speed; and means for controlling the effective area of said valve including a link attached to said valve; a pivotable bar operably connected to said link; a roller operatively connected to and movable along said bar to pivot the same; a servo-motor system for controlling the travel of said roller along said bar including a fluid pressure responsive member exposed to compressor inlet pressure, a second fluid pressure responsive member exposed to compressor discharge pressure, a member connected to each of said pressure responsive members, a tiltable beam supported by both of said members, a chamber, a source of fluid pressure in communication with said chamber, a piston in said chamber, a roller operatively connected to and movable along said tiltable beam connected with said piston and with said first named roller, and means controlled by one of said fluid pressure responsive means for varying the fluid pressure in said chamber; a first cam and a second servo-motor system for controlling the position of said cam including a chamber connected to said fluid pressure source, a piston in said chamber connected to said cam, a spring in said chamber opposing said fluid pressure, and speed responsive means for varying the fluid pressure in said chamber; a second cam actuatable by said first cam for modifying the position of said first named roller over a portion of the acceleration range of said engine; and a third cam for modifying the position

of said roller over another portion of the acceleration range of said engine.

2. An acceleration limiting system for an engine having a compressor, a combustion chamber, and a fuel conduit for conducting fuel to the combustion chamber comprising a metering valve operative to control the fuel flow through said conduit, a head regulator for controlling the pressure drop across said valve, a fluid pressure source for supplying fuel to said conduit having means for varying its output with changes in compressor inlet pressure and engine rotational speed, and means for controlling the effective area of said valve including a link attached to said valve, a pivotable bar operably connected to said link, a roller operatively connected to said link, and movable along said bar to pivot the same, a servo-motor system for controlling the travel of said roller along said bar, means responsive to compressor pressure ratio for controlling said servo-motor system, cam means, operatively connected to said roller for modifying the position of said roller during its travel along said bar, a second servo-motor system for controlling the position of said cam means and engine speed-responsive means operatively connected to said second servo-motor system for controlling the operation of said second servo-motor system and thus the position of said cam means as a function of engine speed, and a cam member operatively connected to said roller for modifying the position of said roller during a portion of its travel along said bar.

3. An acceleration limiting system for an engine as set forth in claim 2 wherein said first named servo-motor system includes a fluid pressure responsive member exposed to compressor inlet pressure, a second fluid pressure responsive member exposed to compressor discharge pressure, a member connected to each of said pressure responsive members, a tiltable beam supported by both of said members, a chamber, a source of fluid pressure in communication with said chamber, a piston in said chamber, a roller tracking on said tiltable beam connected with said piston and with said first named roller, and a means controlled by one of said fluid pressure responsive means for varying the fluid pressure in said chamber.

4. An acceleration limiting system for an engine as set forth in claim 2 wherein said second named servo-motor system includes a chamber connected to a fluid pressure source, a piston in said chamber connected to said cam means, a spring in said chamber opposing said fluid pressure, and speed-responsive means for varying the fluid pressure in said chamber.

5. An acceleration limiting system for an engine having a compressor, a combustion chamber, and a fuel conduit for conducting fuel to the combustion chamber comprising a metering valve operative to control the fuel flow through said conduit, a head regulator for controlling the pressure drop across said valve, a fluid pressure source for supplying fuel to said conduit including means for producing a flow output varying with speed and compressor inlet pressure, and means for controlling the effective area of said valve comprising a link attached to said valve, link actuating means including a roller, means responsive to compressor pressure ratio for positioning said roller, a first cam and a second cam for modifying the position of said roller, speed-responsive means for varying the effective position of said first cam, and a linkage system responsive to movement of said roller for varying the position of said link.

6. An acceleration limiting system for an engine having a compressor, a combustion chamber, and a fuel conduit for conducting fuel to the combustion chamber comprising a metering valve operative to control the fuel flow through said conduit, a head regulator for controlling the pressure drop across said valve, a fluid pressure source for supplying fuel to said conduit including means for producing a flow output varying with speed and compressor inlet pressure, and means for controlling the

effective area of said valve comprising a link connected to said valve, a movable member operatively connected to said link, means responsive to compressor pressure ratio for positioning said member, and first and second means for modifying the position of said member over portion of its travel, one of said means being responsive to changes in speed of said engine.

7. An acceleration limiting system for an engine having a compressor, a combustion chamber, and a fuel conduit for conducting fuel to the combustion chamber comprising a metering valve operative to control the fuel flow through said conduit, a head regulator for controlling the pressure drop across said valve, a fluid pressure source for supplying fuel to said conduit including means producing a flow output varying with speed and compressor inlet pressure, and means for controlling the effective area of said valve comprising linkage means drivably connected to said valve, a movable member operatively connected to said linkage means, servo means responsive to compressor pressure ratio for positioning said member, first cam means and second cam means for modifying the position of said member, said first cam means being movable in response to changes in speed of said engine, said second cam means being fixed in position and operative to override said first cam means during a portion of the travel of said movable member.

8. An acceleration limiting system for an engine having a compressor, a combustion chamber, and a fuel conduit for conducting fuel to the combustion chamber comprising a metering valve operatively connected to said fuel conduit for controlling fuel flow therethrough, a fluid pressure source for supplying fuel to said conduit in such manner that, for a given area, the flow through said valve varies with engine speed and compressor inlet pressure, and means for controlling the effective area of said valve including a link drivably connected to said valve, a movable member operatively connected to said link, means responsive to compressor pressure ratio for positioning said member, and first and second means for modifying the position of said member over portions of its travel, one of said means being responsive to changes in speed of said engine and the other of said means being fixed in position.

9. An acceleration limiting system for an engine having a compressor, a combustion chamber, and a fuel conduit

for conducting fuel to the combustion chamber comprising a metering valve operatively connected to said conduit for controlling fuel flow therethrough, a fluid pressure source for supplying fuel to said conduit in such manner that, for a given area, the flow through said valve varies with engine speed and compressor inlet pressure, and means for controlling the effective area of said valve including a link drivably connected to said valve, a movable member operatively connected to said link, servo means responsive to compressor pressure ratio for positioning said member, a first cam and a second cam for modifying the position of said member, said first cam being movable in response to changes in speed of said engine.

10. An acceleration limiting system for an engine having a compressor, a combustion chamber, and a fuel conduit connected to conduct fuel to the combustion chamber comprising a metering valve operatively connected to said conduit for controlling fuel flow therethrough, a fluid pressure source for supplying fuel to said valve conduit in such manner that, for a given area of said valve, flow through said valve is proportional to the product of engine speed and compressor inlet pressure and valve actuator means for controlling the effective area of said valve such that the area varies as a function of compressor pressure ratio and engine speed over a portion of the acceleration range of the engine and as a function of compressor pressure ratio over another portion of the acceleration range of the engine, said actuator means including first means responsive to compressor pressure ratio, second means operatively connected to said first means and responsive to engine speed, and third means engageable with said first means for overriding said second means over the last mentioned portion of the acceleration range of the engine.
